UNITED STATES PATENT OFFICE.

CHARLES E. WICKE, OF MOUNT VERNON, NEW YORK, ASSIGNOR TO A. C. WICKE MANUFACTURING COMPANY, OF NEW YORK, N. Y., A CORPORATION OF NEW YORK.

DISPLAY CASE.

Application filed March 17, 1927. Serial No. 175,950.

This invention relates to show or display cases and more particularly to glass enclosed cases of the refrigeration type.

Show cases of the above character are extensively employed for the display of perishable articles, such as meats, produce and the like. In the exhibition of such articles, it is, of course, desirable to present them to the best advantage and at the same time maintain a low temperature surrounding atmosphere. It is preferable to construct show cases for this purpose with the main or foremost window so arranged that the merchandise will be displayed to the best advantage and unobscured by reflection or refraction of light rays. Furthermore, since considerable moisture condenses on windows in show cases of this type it is essential to provide means for receiving and removing the condensate and to prevent an accumulation of water in the compartment containing the displayed goods.

An object of the present invention is therefore to provide a display case having the window thereof so constructed and arranged as to offer the least obstruction to the visibility of the articles displayed within the case.

Another object of the invention is to provide a combined support and drainage element for said window.

A further object of the invention is to provide a simple and effective show case which may be quickly assembled and of a sanitary and durable construction.

The present invention is mainly concerned with the foremost or show window and its supporting structure.

It has been found that if a show window is disposed in a vertical or inclined plane, the visibility of the objects within the case is interfered with by the refraction or reflection of light passing through the glass and only when the observer takes a certain relative position is the best effect or greatest visibility made possible and the same is also true of the semi-circular show windows. This is, of course, a disadvantage since the show case is usually a mode of advertisement of the merchant's wares and it is to his benefit to have his displayed articles at all times presented in such manner as to be the most effective.

It has been found that by providing a combined vertical and cylindrical forma-

tion of show window that objectional reflection and refraction of light, which had heretofore obscured clear vision, is greatly reduced and that articles displayed behind a show window of such form, are clearly visible by an observer from all angles. Usually, show cases of the refrigeration type are set below the line of sight of the average person. It has been found that a person's range of vision is free from interference when travelling from the upper to the lower portion of the interior of a compartment provided with the present type of window. The exact explanation for this is not here attempted, but it is believed that the variation in the surfaces, where the greatest amount of light is absorbed, are least effective to sight of one standing in position to view the contents of the compartment. The eye travels over the rounded surface in line with the radius thereof and then at an angle to the straight side or vice versa.

The result is that the reflections and refractions that heretofore occurred are neutralized and the articles may be viewed clearly without discomfort.

The invention also provides a supporting ledge for the show window which ledge is in transverse cross section substantially of S-shape. One portion of the ledge provides an outer molding or bead which serves as a seal and permits exterior condensate to flow over the connection between the window and the ledge. Another portion of the ledge is constructed in the form of a trough to receive interior condensate and is provided with drain apertures to direct the flowing moisture out of the compartment. The ledge may be made of any hard or sanitary material, as non-corrosive metal, enamel ware, porcelain, tile or the like and may be provided in sections having male and female interlocking members so that a long ledge may be built or united as an integral member. The supporting ledge is also so constructed as to accommodate vertical, sloping or rounded show glasses or a plurality thereof.

For the purpose of supporting a show glass, brace members are provided and the ledge is formed with sockets to receive dowel pins on the brace members. The members are disposed in a given spaced relation and their upper ends may be provided with a

flange for attachment to the structure of the compartment or case.

The invention will be more fully understood by reference to the accompanying drawings in which,

Fig. 1 is a vertical sectional view of a refrigerator type of show case with the present invention applied thereto;

Fig. 2 is an enlarged perspective view of a glass supporting ledge and drain trough made in accordance with the present invention;

Fig. 3 is a fragmentary plan view of the ledge shown in Fig. 2;

Fig. 4 is a sectional view of a portion of a show case made approximately one-half the actual size illustrating the relation of curvature to the straight portion and also showing a brace member and tie piece 20 or strip;

Fig. 5 is a view taken on line V—V in Fig. 4 but enlarged to approximately full size; and

Fig. 6 is a modified form of ledge adapted to support a plurality of show case glasses.

The selected embodiment of the invention may comprise an ice cooled show case or compartment which, as a whole, is designated by the reference numeral 10, comprising an upper wall 11 having any suitable type of door 12 supported on cross pieces 13 and 14. The compartment may have a rear wall 15 and a bottom wall 16, the latter including a slab of marble supported on cross members 18 and 19 and partitions 20 and 21, and a filling of cork 22' and 23' may be provided to insulate the compartment.

A front wall 22 is provided which in conjunction with a ledge 23 and window 24 completes the enclosure, it being understood that end walls of any suitable form (not shown) may be provided. The greater part of the structure just described, is common to this type of case, the present invention residing in the improved form of ledge and the show window supported thereby. This ledge may be of any convenient length and each length may have V or other shaped male and female portions 24' and 25 so that a plurality of sections may be united to form a continuous length to receive the lower edge of the glass 24. For this purpose, the ledge is provided with a slot or groove 26 having one side 27 thereof perpendicular and the opposite side 28 inclined. In addition, the bottom of the groove is formed with a supplemental inclined groove 29 adjacent to the inclined wall or side 28. This construction affords two seating areas 31 and 32. The surface 31 is adapted to receive the end of a glass having a vertical portion and the surface 32 is adapted to receive the edge of an inclined or curved glass 33 indicated in dotted lines in Fig. 2. The ledge 23 is so formed as to provide a flange or bead 34

which covers the crevice between the glass and its seat as well as the seam at the upper edge of the front wall 22, a suitable recess 34' being provided in the ledge to receive the edge of the said wall. It will be noted that the bead is so arranged that its upper edge 35 is contiguous with the glass 24 which is vertical and the same relation is attained when an inclined glass 33 is employed. Thus an effective seal may be had and any condensed moisture flowing downwardly will not enter the compartment nor accumulate along the bead which is fashioned with a curvature to hasten the removal of condensate. The portion 36 of the ledge extending within the compartment is formed of trough shape and provides a gutter to receive condensate flowing from the interior wall of the glass. Apertures 37 are provided to permit a discharge of the condensed moisture from the trough, any suitable number of apertures being employed.

Although, as indicated, various shaped show windows may be used with the present ledge, it has been found preferable to employ the shape as more clearly shown in Fig. 4. This window has a straight side or portion 38 continuous with a curved portion 39.

When in position in a show case the window 24 is positioned with the straight side 95 lowermost. This particular form of show window is exceptionally effective in permitting clear vision within the case and it has been found, through extensive thought and experiment, that the best results are obtained when the external curved surface of the glass has a radius of about seven and three-quarter inches tangent to a plane surface. This latter surface is in a window of practical size about nine and one-half inches 100 between its point of tangency to the curved surface and its lower edge. Show windows of the above type may, of course, be of different sizes but if the same ratio is maintained between the tangential surfaces the 110 desired result is obtained. Thus the total vertical length or projection of the surface of the show case window may be nine and one-half inches, for the straight portion plus seven and three-quarter inches for the radius 115 of the curvature and if the ratio of these two dimensions is maintained the same desirable result will follow with different size windows.

The show windows are usually produced 120 in lengths or sections and if the case is of such length as to require more than one section, a brace member 40 is provided of such shape as to present a flat side 41 for contact with the inner surface of the glass. For the 125 purpose of strengthening the brace, the same may be formed with a fin or web 42 as shown in the sectional view (see Fig. 5). The lower end 43 of the brace member is shaped to snugly fit a curved portion of the ledge 130

23 and is provided with a dowel pin 44 which may extend into a suitable aperture provided in the ledge. The upper end of the brace may have a flange 45 provided with 5 screw apertures for attachment to the cross member 14 of the case. As shown in Fig. 5 two adjacent windows 24 may rest on the brace member with their edges in spaced relation. A cover or tie strip 46 is provided 10 and formed with a central rib 47 which fills the space between the adjacent windows and is provided with extended sides which lap the edges of the windows. The strip 46 may be secured by screws 50 of any suitable 15 number which extend through the strip and into the brace member 40. Thus the said brace member not only serves as a rigid support for the glass but in conjunction with the strip 46 effectively seals the same between two adjacent sections of the window. If desirable, the brace members may be used 20 alone, that is, between the ends of the windows as additional supports where an exceptionally long length of show window 25 glass is used.

The ledge 23 may, as shown in Fig. 6, be provided with several grooves 51 and 52 to accommodate several glasses, as when it is desirable to provide the show window in the 30 form of a double transparent wall for heat insulating purposes. This type of ledge is generally the same as the one previously described and it will be noted that in addition to supporting the show windows, an end 35 53 of the ledge may serve as a support for the slab 17 and that the lower flattened portion 54 of the ledge may rest on blocks 55 giving strength and rigidity to the structure.

It will readily be appreciated that by reason of the present invention a simple and effective show case construction is obtained 40 and that the same may be quickly and conveniently assembled or disassembled. Furthermore, the various points or lines of union are so arranged and united that a high 45 degree of sanitation is possible.

Although a preferred embodiment of the invention is shown and described herein, it is to be understood that the same may be varied or modified without departing from 50 the spirit and scope of the appended claims.

What is claimed is:

1. A display case comprising a base portion and a display portion disposed above said base portion and a ledge extending 55 along the upper forward edge of said base portion, said ledge having means for receiving a portion of said base portion and means for receiving a portion of said display portion and a trough extending inwardly from 60 said ledge, said ledge being formed in sections provided with interlocking means to prevent transverse movement.

2. A display case comprising a base portion and a display portion disposed above 65 said base portion and a ledge extending along the upper forward edge of said base portion, said ledge having means for receiving a portion of said base portion and means for receiving a portion of said display portion, said last-mentioned means consisting of a groove so designed as to receive either 70 vertical or slanting show glass.

In testimony whereof I affix my signature.

CHARLES E. WICKE.
